(57) **CLAIM**

The ornamental design for a mop, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top perspective view of a mop showing our new design;

FIG. 2 is a left-side view thereof;

FIG. 3 is a right-side view thereof;

FIG. 4 is a rear view thereof;

FIG. 5 is a front view thereof;

FIG. 6 is a top view thereof; and,

FIG. 7 is a bottom view thereof.

The particular colors and color contrasts depicted in the drawings form a characteristic feature of the claimed design. Broken lines and shading in the drawings indicate portions which form no part of the claimed design.
